(57) **CLAIM**

The ornamental design for a head-mounted display, as shown and described in FIGS. 1-8.

DESCRIPTION

FIG. 1 is a front left perspective view of a support structure of a head-mounted display, according to an embodiment.

FIG. 2 is a rear right perspective view of the support structure according to the embodiment of FIG. 1.

FIG. 3 is a front view of the support structure according to the embodiment of FIG. 1.

FIG. 4 is a rear view of the support structure according to the embodiment of FIG. 1.

FIG. 5 is a left view of the support structure according to the embodiment of FIG. 1.

FIG. 6 is a right view of the support structure according to the embodiment of FIG. 1.

FIG. 7 is a top view of the support structure according to the embodiment of FIG. 1; and,

FIG. 8 is a bottom view of the support structure according to the embodiment of FIG. 1.

In the drawings, the dashed lines depict portions of the article that form no part of the claimed design.
